[57] **ABSTRACT**

Apparatus for effecting development of an electrostatic latent image comprising a plurality of magnetic developing rollers positioned with intersecting magnetic force fields for effecting a blanket of developing material extending about and between the developing rollers adjacent an electrostatic latent image-bearing surface. A cylindrical roller, which may be electrically biased, is positioned between the magnetic developing rollers adjacent the electrostatic latent image bearing surface to enhance image development.

FIG. 2

ELECTROSTATIC LATENT IMAGE DEVELOPMENT APPARATUS

BACKGROUND OF THE INVENTION

This invention relates to the development of electrostatic latent images and, in particular, to an apparatus for developing electrostatic latent images utilizing a magnetizable carrier material and an electroscopic toner powder.

More specifically, this invention relates to a magnetic brush development apparatus having an extended development zone.

In the method of development of electrostatic latent images by the application of electroscopic toner powder (for example, of the type disclosed in Carlson U.S. Pat. No. 2,940,934) through the use of a magnetizable carrier material, referred to in the art as magnetic brush development, there is generally employed a single-magnetic brush closely spaced adjacent a surface carrying latent electrical charges in image configuration. As the electrostatographic art has progressed, the time in which the latent image is in contact with the development system has decreased because of the increased linear speed of the latent image-bearing surface. Therefore, many attempts have been made to increase the length of this development zone. However, due to space constraints required of a commercial reproducing apparatus the addition of a plurality of development units has not been effective to solve this problem. One attempt to increase the effective length of the development zone without adding to the size of the development unit has been by positioning two magnetic brush developing rollers adjacent each other and adjacent an electrostatic latent image-bearing surface such that the magnetic fields emitted from the development rollers intersect to convey developer material across the space between the rollers and in contact with the latent electrical charges on the image-bearing surface. While such a system provides an increased effective development zone and has proven to be very successful, it has been found in certain applications wherein the magnetizable carrier material is of a certain size, that the weight of the developer material is such that gravitational forces overcome the magnetic field emitted from the developing rollers and sufficient contact is not maintained between the developer material and the electrostatic latent image-bearing surface throughout the entire development zone as is desired.

SUMMARY OF THE INVENTION

Therefore, it is an object of this invention to improve apparatus for developing electrostatic latent images.

Another object of this invention is to increase the effective development zone of developing apparatus.

A further object of this invention is to insure complete contact of developer material with an electrostatic latent image-bearing surface the development of which is effected by a plurality of magnetic brush development rollers positioned adjacent one another and the electrostatic latent image-bearing surface such that their magnetic fields intersect to convey developer material across the space therebetween in contact with the latent image-bearing surface.

These and other objects are attained in accordance with the present invention wherein there is provided a plurality of magnetic brush developing units positioned adjacent each other and an electrostatic latent image-bearing surface and including a rotatable cylindrical member positioned between the developing units and the latent image-bearing surface to effect image development throughout the extended developing zone.

Further objects of this invention, together with additional features contributing thereto and advantages accruing therefrom, will be apparent from the following description of one embodiment of the invention when read in conjunction with the accompanying drawings.

BRIEF DESCRIPTION OF THE DRAWINGS

FIG. 1 is a mechanical schematic of an automatic xerographic reproducing machine utilizing the invention of this application;

FIG. 2 is a front perspective view of the developing apparatus to better illustrate the developing units and the cylindrical roller which enhances development of the electrostatic latent image throughout the extended developing zone; and

FIG. 3 is a schematic section of the apparatus shown in FIG. 2 taken along lines 3-3.

DESCRIPTION OF THE PREFERRED EMBODIMENT

As shown in FIG. 1, there is illustrated a cross section mechanical schematic of an automatic xerographic reproducing machine utilizing this invention. As in all electrostatographic systems, illustrated by the xerographic reproducing machine shown, a light image of a document to be reproduced is projected 3 onto a photosensitive surface 1 to form an electrostatic latent image thereon. Thereafter, the latent image is developed 4 to form an electroscopic toner powder image in the configuration of the latent image on the photoreceptor surface. The powder image may then be transferred 5 to a support material to which it may be permanently fixed as by heat fusing, or the toner powder may be permanently affixed to the photoreceptive surface depending on the method of electrostatographic imaging employed as is well known in the art.

Referring now to FIGS. 2 and 3, the developing apparatus 50 extends the width of the photoreceptor 1 and is substantially enclosed except for an opening adjacent the photoreceptor whereat development of the latent electrostatic image is effected, and an opening 11 upon which a toner powder dispenser 10 is positioned to replenish the toner depleted from the developer mixture during development of the electrostatic images. Within the housing of the developer apparatus there is a sump 51 at the lowermost portion of the housing containing developer material comprising magnetizable carrier material and colored electroscopic toner particles. The toner particles are many times smaller than the carrier material and, due to a triboelectric relationship therebetween, substantially uniformly coat the carrier material.

The developing apparatus 50 is positioned within the automatic xerographic reproducing machine adjacent to the photoreceptor 1 by suitable brackets and braces appropriately secured to the developing apparatus and the frames of the machine. A suitable mounting 12 is provided on the top of the developing apparatus between cover plates 52 and 53 to position and retain the toner powder dispenser 10.

Development of the electrostatic latent image is effected by a blanket of developing material formed between a pair of adjacent magnetic rollers 70 and 80 positioned such that their magnetic force fields intersect to effect formation of a blanket of developing material upon the rollers 70 and 80, and in the space therebetween adjacent the photoreceptor 1. The magnetic rollers 70 and 80 comprise outer cylinders 71 and 81, respectively, of a nonmagnetic material, such as aluminum, extending the width of the developer housing with elongated bar magnets 72 and 82, respectively, extending nearly the full length of each cylinder. The bar magnets 72 and 82 are each supported, for example, on a ferromagnetic bar 73 having rod 74 secured to each end, as by welding, and securely fastened in mounting blocks 75 appropriately secured to side frame plates 54 of the developer apparatus. The outer cylinders 71 and 81 of nonmagnetic material are each mounted for rotation within the developer housing by means of suitable bearing surfaces 76 carried by the side frame plates 54 of the developer housing (FIG. 2). One end of the cylinder is enclosed by a cap 77 having a central opening therein, through which the rod portion 74 passes, and is rotatably supported thereabout in the frame plate 54 by the bearing 76. The driven end is enclosed by an end cap 78 rotatably supported in suitable bearings in the side frame plate 54 and having a drive gear 89 secured thereto to effect rotation of each cylinder. The rotational drive for all other rotary components of the developing apparatus 50 is derived from drive gear 89 by means of a suitable timing belt (not shown) engaging suitable drive connections on each component. In this manner the outer cylinders may be

rotatably driven about the stationary elongated bar magnets

72 and 82. The polar orientation of the elongated bar magnets is arranged such that the magnetic force fields project through the walls of the nonmagnetic cylinders 71 and 81 to form the magnetizable carrier material into a brushlike configuration in a manner well known in the art.

As best shown in FIGS. 2 and 3, the peripheral walls of the cylinders 71 and 81 are positioned in closely spaced relationship adjacent to one another. During a development cycle when both cylinders are rotating in synchronism about their respective stationary bar magnets 72 and 82, the brush bristles produced by action of the magnetic field emanating from the magnets acting upon the magnetizable carrier material will form on the upper region of the cylinder 71 within the magnetic field emanating from magnets 72 and the under surface of the electrostatic image-bearing photoreceptor 1. These bristles are formed during the developing cycle, and are produced by the magnetic field from the bar magnets 72. When the bristles are moved by the cylinder 71 out of the influence of magnet 72 beyond the closest distance between the photoreceptor 1 and the cylinder 71, they are attracted by the greater magnetic field of the magnet 82 which is stronger at this point than the diminished strength of the magnetic field attributed to the magnet 72. The developer material is carried therealong during rotation of the cylinder 81 until the material reaches a point beyond the development zone whereat the magnet field is diminished and the carrier material and toner particles drop off the cylinder 81 and back into the sump portion 51 of the developer apparatus. A suitable stripping mechanism such as a nonmagnetizable doctor blade 96 may be utilized to insure that the magnetizable developer material is removed from the cylinder 81.

During movement of the developer material through the development zone between the two cylinders 71 and 81, the magnetizable developer material is in the form of a blanket extending the entire distance (FIG. 3) between the two cylinders and in contact with the photoreceptor 1. Therefore, the width of the development zone is larger than the sum of the individual development zones for either of the magnetic rollers 71 or 81.

In order to insure that the blanket of developer material contacts the electrostatic latent image-bearing surface throughout the extended development zone, a rotatable wire brush or other cylinder 60 is positioned between the magnetic developing rollers 70 and 80, adjacent the latent image-bearing surface 1. The cylinder 60 is rotatably supported in suitable bearing surfaces carried by side frame plates 54 and may be positively driven, or act as an idler, and functions to support the developer material as it passes from cylinder 71 to cylinder 81. The cylinder 60 prevents the developer tufts from collapsing under their own weight as they pass from the magnetic field emanating from roller 70 into the magnetic field emanating from roller 80. In addition to the cylinder 60 supporting the developer material in brushlike tufts adjacent the latent image-bearing surface, by applying a suitable electrical bias, such as 250 volts, to the cylinder a development electrode effect will occur to further enhance image development.

After the developer material has effected development of the latent image on the photoreceptor surface, the material is removed from the cylinder 81 and passed to the sump portion 51 of the developer apparatus. A developer conveyor 20 is rotatably mounted within the side frame plates 54 of the developer apparatus by suitable bearings and carries the developer material from the sump portion to be introduced to the magnetic developing rollers 70 and 80. The developer conveyor comprises a plurality of spaced buckets 21 carried by a belt 22 appropriately driven by a shaft 23 rotatably mounted in suitable bearing surfaces in the side frame plates 54 and driven by means of a gear (not shown) suitably secured to one end of the shaft 23 and engaging a suitable drive system.

While there has been shown and described one embodiment of the invention, it is intended that the invention be not limited to the exact form shown and described or to anything less than the whole of the invention as set forth in the appended claims.

What is claimed is:

1. Apparatus for developing a support surface carrying latent electrical charges selectively retained in image configuration including

5 a first magnetic field emitting means to convey a quantity of magnetizable developer material in contact with a support surface to be developed,

10 a second magnetic field emitting means spaced therefrom with the respective magnetic fields intersecting to convey developer material across the space therebetween in contact with the latent electrical charges to effect the development thereof, and

15 means positioned between said first and second magnetic field emitting means to support developer material conveyed across the space therebetween in contact with the support surface.

2. Apparatus for developing a support surface having latent electrical charges selectively retained in image configuration including

20 a first magnetic field emitting means to move a quantity of magnetizable developer material in contact with a support surface having latent electrical charges selectively retained in image configuration,

25 a second magnetic field emitting means spaced therefrom with the respective emitted magnetic fields intersecting to move magnetizable developer material in contact with the support surface through the space between said first and second magnetic field emitting means to effect the development of the latent electrical charges selectively retained in image configuration, and

30 means positioned between said first and second magnetic field emitting means to support developer material in contact with the support surface as the developer material is moved between said magnetic field emitting means in response to the intersecting of their respective magnetic fields.

3. Apparatus for developing a support surface having latent electrical charges selectively retained in image configuration including

35 a plurality of spaced cylinders rotatably supported adjacent a support surface having latent electrical charges selectively retained in image configuration to convey a quantity of magnetizable developer material thereto for effecting the development thereof,

40 magnetic field producing means supported within each of said cylinders to emit a magnetic field passing therethrough and intersecting with the magnetic field emitted from within another of said spaced cylinders,

45 means to rotate said cylinders to convey a magnetizable developer material into contact with the support surface and across the space between said cylinders in response to said intersecting magnetic fields for effecting the development of the latent image on the support surface, and

50 means positioned between said plurality of spaced cylinders adjacent the support surface to support the magnetizable developer material in brushlike tufts in response to the magnetic fields emitted through said cylinders.

4. The apparatus of claim 3 wherein said means to support the magnetizable developer material in brushlike tufts in response to the magnetic field emitted through said cylinders includes

55 a rotatable cylinder supported adjacent the latent image bearing support surface with the magnetizable developer material passing therebetween.

5. Apparatus for developing a support surface having latent electrical charges selectively retained in image configuration including,

60 a plurality of spaced cylinders rotatably supported adjacent a support surface having latent electrical charges selectively retained in image configuration to convey a quantity of magnetizable developer material thereto for effecting the development thereof,

magnetic field producing means supported within each of said cylinders to emit a magnetic field passing therethrough and intersecting with the magnetic field emitted from within another of said spaced cylinders, means to rotate said cylinders to convey a magnetizable developer material into contact with the support surface and across the space between said cylinders in response to said intersecting magnetic fields for effecting the development of the latent image on the support surface, and

10 an electrically conductive rotatable cylinder supported adjacent the latent image-bearing support surface between adjacent pairs of said spaced cylinders to support the magnetizable developer material in brushlike tufts in response to the magnetic fields emitted through said cylinders.

15 6. The apparatus of claim 5 wherein said electrically conductive cylinder is electrically biased to a potential of approximately 250 volts.

7. Apparatus for developing latent electrostatic charge patterns on a support surface comprising,

a first magnetic field emitting means for conveying a quantity of magnetizable developer material over the support surface to be developed,

20 a second magnetic field emitting means for conveying a quantity of magnetizable developer material from said first magnetic field emitting means over the support surface to be developed, said second magnetic field emitting means being spaced from said first magnetic field emitting means such that the respective magnetic fields are in overlapping relationship with each other, and

25 means positioned between said first magnetic field emitting means and said second magnetic field emitting means for supporting developer material conveyed from said first magnetic field emitting means to said second magnetic field emitting means in contact with the support surface to be developed.

30 8. Apparatus for developing latent electrostatic charge patterns on a support surface comprising,

a first magnetic field emitting means for moving a quantity of magnetizable developer material over the support surface to be developed,

35 a second magnetic field emitting means for moving a quantity of magnetizable developer material over the support surface to be developed, said second magnetic field emitting means being spaced from said first magnetic field emitting means with the respectively emitted magnetic fields intersecting therebetween to support magnetizable developer material across the space between said first and said second magnetic field emitting means, and

40 means positioned between said first and said second magnetic field emitting means for supporting developer material in contact with the support surface to be developed as the developer material is transported from said first magnetic field emitting means to said second magnetic field emitting means.

45 9. Apparatus for developing latent electrostatic charge patterns on a support surface comprising,

a first cylindrical member supported for rotation adjacent a support surface having latent electrostatic charge patterns thereon which are to be developed,

50 a first magnetic field producing means supported within said first cylindrical member for attracting a quantity of magnetizable developer material to the surface of said cylindrical member for movement of said cylindrical member over said support surface,

55 a second cylindrical member supported for rotation adjacent said support surface and spaced from said first cylindrical member,

60 a second magnetic field producing means supported within said second cylindrical member, the field from said second magnetic field producing means extending across

the space between said first and said second cylindrical members into the field of said first magnetic field producing means to attract a quantity of magnetizable developer material from the surface of said first cylindrical member to the surface of said second cylindrical member for movement by said second cylindrical member over said support surface, and

65 means positioned between said first and said second cylindrical members for supporting the magnetizable developer material proximate to the support surface as the developer material is moved across the space between said first and said second cylindrical members.

10. Apparatus for developing latent electrostatic charge patterns on a support surface comprising,

a first cylindrical member supported for rotation adjacent a support surface having latent electrostatic charge patterns thereon which are to be developed,

a first magnetic field producing means supported within said first cylindrical member for attracting a quantity of magnetizable developer material to the surface of said cylindrical member for movement by said cylindrical member over said support surface,

a second cylindrical member supported for rotation adjacent said support surface and spaced from said first cylindrical member,

a second magnetic field producing means supported within said second cylindrical member, the field from said second magnetic field producing means extending across the space between said first and said second cylindrical members into the field of said first magnetic field producing means to attract a quantity of magnetizable developer material from the surface of said first cylindrical member to the surface of said second cylindrical member for movement by said second cylindrical member over said support surface, and

a support member of generally cylindrical configuration positioned intermediate said first and said second cylindrical members and adapted for rotation to support the magnetizable developer material proximate to the support surface as the developer material is moved across the space between said first and said second cylindrical members.

11. Apparatus for developing latent electrostatic charge patterns on a support surface comprising,

a plurality of cylindrical members supported in spaced relationship to each other adjacent said support surface for moving magnetizable developer material over said support surface,

magnetic field producing means supported within said cylindrical members, the respective fields from said magnetic field producing means extending across the spaces between adjacent ones of said cylindrical members in overlapping relationship to attract magnetizable developer material from the surfaces of precedingly adjacent cylindrical members to the surfaces of succeedingly adjacent cylindrical members as the developer material is moved by said cylindrical members over said support surface, and

means positioned between adjacent pairs of said cylindrical members for supporting the magnetizable developer material proximate to the support surface as the developer material is moved across the spaces between said cylindrical members.

12. Apparatus for developing latent electrostatic charge patterns on a support surface comprising,

a plurality of generally cylindrical members supported in rotatable spaced relationship to each other adjacent said support surface for moving magnetizable developer material in brushlike tufts over said support surface,

magnetic field producing means supported within said cylindrical members, the respective fields from said magnetic field producing means extending across the spaces between adjacent ones of said cylindrical members in

overlapping relationship, said overlapping fields forming brushlike tufts of magnetizable developer material on the surfaces of said cylindrical members and attracting the magnetizable developer material from the surfaces of preceedingly adjacent cylindrical members to the surfaces of succeedingly adjacent cylindrical members as the developer material is moved by said cylindrical members

over said support surface, and means positioned between adjacent pairs of said cylindrical members for supporting the magnetizable developer material proximate to the support surface as the developer material is moved across the spaces between said cylindrical members.
